(Cl. D9—294)

FIGURE 1 is a perspective view of a holder for a squeeze tube showing my new design;

FIGURE 2 is another perspective view with a squeeze tube being shown in broken lines for illustrative purposes only; and

FIGURE 3 is a top plan view on an enlarged scale.

The side opposite that seen in FIGURES 1 and 2 is substantially the same in appearance as the side shown.

I claim:

The ornamental design for a holder for a squeeze tube, as shown and described.
